UNITED STATES PATENT OFFICE.

LYNN G. RILEY, OF WILKINSBURG, PENNSYLVANIA, ASSIGNOR TO WESTINGHOUSE ELECTRIC & MANUFACTURING COMPANY, A CORPORATION OF PENNSYLVANIA.

CONTROL APPARATUS.

1,401,645.

Specification of Letters Patent. Patented Dec. 27, 1921.

Application filed June 15, 1917. Serial No. 174,918.

To all whom it may concern:

Be it known that I, LYNN G. RILEY, a citizen of the United States, and a resident of Wilkinsburg, in the county of Allegheny and State of Pennsylvania, have invented a new and useful Improvement in Control Apparatus, of which the following is a specification.

My invention relates to control apparatus and especially to motor-reversing switches of the power-operated drum type.

One object of my invention is to provide a power-operated mechanism for a rotatable motor-reversing drum, whereby the drum may be moved in a step-by-step manner in the same direction to reverse the motor connections with each step.

More specifically stated, it is an object of my invention to provide an electrically-controlled fluid-pressure-operated device for actuating the above-mentioned drum in the same direction through a plurality of positions to alternately effect "forward" and "reverse" connections of the governed motor, the energization of the electrically controlled device being dependent upon the drum position.

Another object of my invention is to provide a relatively inexpensive and compact motor-reversing device, wherein a single power-actuated engine is employed in lieu of the doubly-acting power devices of the prior art.

My invention may best be understood by reference to the accompanying drawings, wherein Figure 1 is a view, in side elevation, with parts broken away, of a motor-reversing device constructed in accordance with my present invention; Fig. 2 is a view, chiefly in end elevation but partially in section, of the apparatus shown in Fig. 1; and Fig. 3 is a diagrammatic view of a control system illustrating the preferred use of the invention in connection with the reversal of an electric motor.

Referring to Fig. 1 and Fig. 2 of the drawings, the apparatus shown comprises a rotatable drum member 1 having a main-circuit portion 2 and an auxiliary-circuit portion 3 for purposes to be subsequently set forth, both portions being concentrically mounted upon an operating shaft 4; an electrically-controlled, fluid-pressure-operated actuating device 6 for the rotatable drum 1, and power-transmitting means 7 interposed

between the drum 1 and the actuating device 6.

The main-circuit portion 2 of the drum embodies a plurality of sets of main-circuit contact strips or segments 10 of familiar configurations for suitably engaging a plurality of main control fingers 11, which are mounted upon a stationary finger-base 12 that extends along one side of the drum, in accordance with the usual construction. The circuit connections of the contact segments 10 and the control fingers 11 will be subsequently set forth in detail, in connection with the description of Fig. 3.

The auxiliary-circuit drum portion 3 carries a plurality of suitably shaped auxiliary-circuit contact plates or segments 13 and a plurality of co-operating stationary control fingers 14 which may also be mounted upon the finger-base 12. The auxiliary contact members 13 and 14 are employed for the purposes of controlling the energization of the actuating device 6 and also of a line switch for the motor to be governed, as hereinafter fully described in connection with Fig. 3.

If desired, a handle member 15 may be detachably secured to one end of the drum shaft 4 to permit manual operation of the reverser.

The power-transmitting means 7, in general, comprises a notched disk or ratchet member 20 and a co-operating pawl or arm 21 that is actuated by the fluid-pressure-operated device 6 in a manner to be described.

The device 6 comprises an operating casting or cylinder 25, within which a piston 26, having a rod or stem 27 pivotally associated with the pawl 21, is adapted to travel, being biased to the illustrated lower position through the agency of a coil spring 28 that is located within the cylinder 25. Fluid pressure from any suitable source (not shown), upon the actuation of a controlling valve device 29, is permitted to flow to the lower end 30 of the cylinder 25 to effect an upward actuation of the piston 26 in opposition to the pressure of the biasing spring 28.

The controlling valve device 29 is preferably of a familiar electrically-controlled type having duplex actuating coils 33^f and 33^r (see Fig. 3) that are provided with suitable terminals 31. The two actuating coils may be arranged, in any suitable manner,

within the usual incasing member for actuating the valve rod in accordance with a well-known construction. The cylinder 25 and the valve device 29 may conveniently be 5 mounted in the respectively illustrated positions upon a common base 32, whereby a relatively compact and neat structure, which is, nevertheless, readily accessible for inspection and maintenance, is provided. Inasmuch as the particular type of valve proper 10 that is utilized for supplying fluid pressure to the operating cylinder 25, upon the energization of either actuating coil, is immaterial to my present invention, any well-known 15 form of plug valve may be employed, and I have not deemed it necessary to illustrate or describe the valve in further detail.

The ratchet member 20 is provided with a plurality of teeth 35, the distance between 20 successive teeth corresponding to the circumferential distance apart of the operating positions of the motor-reversing drum 1, as diagrammatically illustrated in Fig. 3. The pawl 21 is provided with a suitable notching 25 tip 36 and is pivotally mounted at 37, near the upper end of the piston stem 27 and externally to the operating cylinder 25. For the purpose of permitting the necessary play or lost-motion of the coöperating parts, 30 while still insuring that the pawl 21 will always engage the proper tooth of the ratchet member, a suitably bent wire-spring 38 is secured to the piston stem 27 and bears against the pawl 21, which thus has a resili- 35 ent oscillatory movement about the pivotal point 37.

Only a brief description of the operation of the apparatus just described will be necessary. Assuming that the various parts of 40 the apparatus occupy the respectively illustrated positions, upon energization of the actuating coil 33_f or 33_r for the controlling valve device 29, fluid pressure is admitted beneath the piston 26, which is thereupon 45 upwardly actuated, in opposition to the pressure of the coil spring 28, to cause the tip 36 of the pawl 21 to engage the adjacent ratchet tooth 35 and move the drum 1 to the next operative position, whereupon the active coil 50 of the controlling valve device 29 may be de-energized and is, in fact, deenergized as soon as the drum reaches the desired position, to permit the coil spring 28 to retract the piston 26 and the pawl 21 to the illustrated position in readiness for the next ad- 55 vancing movement thereof.

Without the necessity of detailed illustration or description, it will be understood that preferably a position-accentuating 60 mechanism of the familiar star-wheel type is utilized in connection with the present invention to further insure that the drum is always actuated to the exact position desired, whereby burning and pitting of contact members is obviated.

Reference may now be had to Fig. 3, wherein the system shown comprises a supply circuit having conductors "Trolley" and "Ground;" an electric motor having an armature A1 and a field winding F1 of the series type; an electrically-controlled line switch LS for connecting the motor to the supply circuit; the motor-reversing drum 1 and an auxiliary manually actuated master-reverser 39 which primarily governs the operation of the system by completing certain circuits to be described, in conjunction with a suitable source of auxiliary energy, such as a battery B.

It will be understood that the number of required sets of main-circuit contact segments 10 and auxiliary-circuit contact segments 13, in order to permit the desired actuation of the drum 1 in the same direction through a plurality of equally spaced operative positions, will depend upon the necessary distance between adjacent contact segments and upon the diameter of the drum. The number of positions chosen will, of course, correspond to the number of ratchet 90 teeth 35. Consequently, it will be appreciated that my present invention is not limited, in its application, to the use of any particular number of operative positions or sets of contact members.

Assuming that the motor-reversing drum 1 occupies the illustrated position and that the master reverser 39 is actuated to its forward position marked "For," an auxiliary circuit is completed from the positive terminal of the battery B through conductor 40, control fingers 41 and 42, which are bridged by contact segment 43 of the master reverser, conductor 44, certain combinations of the main-circuit contact segments 13 and coöperating control fingers 14, conductor 45, actuating coil 46 for the line switch LS and conductors 47 and 48 to the negative battery terminal.

The main-motor circuit is thus completed 110 from the trolley through conductor 50, the coöperating contact members 51 of the closed line switch LS, conductor 52, armature A1, conductor 53, certain combinations of the main-circuit contact segments 10 and co- 115 operating control fingers 11, conductor 54, field winding F1, conductor 55, another combination of contact members 10 and 11, and conductor 56 to the negative supply circuit conductor Ground.

Assuming that the circuit connections are initially as shown and that it is desired to reverse the motor connections, the master reverser 39 is thrown to its reverse position marked "Rev." whereby a circuit is established from the positive battery conductor 40, through control fingers 41 and 60 which are bridged by contact segment 61 of the master reverser, conductor 62, a certain combination of auxiliary contact segments 130

13 and control fingers 14, conductor 63, the actuating coil 33^r of the controlling valve device 29 and conductor 48 to the negative battery terminal. The fluid-pressure-operated device 6 is thereupon actuated in the previously described manner to move the drum 1 to the next operative position marked "Rev." whereupon the energizing circuit of the actuating coil 33^r is interrupted.

- 10 In the new position, connection is established, through certain of the auxiliary contact members 13 and 14, between the conductors 62 and 45, whereby the line switch LS is energized and closed, as already set forth. By reason of the familiar arrangement of main-circuit contact members 10, the actuation of the drum 1 to the new position serves to reverse the electrical relations of the armature A1 and the field winding 20 F1, since conductors 53 and 55 are directly joined and conductors 54 and 56 are directly connected through the coöperating contact members 10 and 11.

When the drum 1 occupies its "reverse"

- 25 position and the master reverser 39 is moved to its "forward" position, a connection through the auxiliary-circuit coöperating contact members 13 and 14 joins conductors 44 and 65, whence circuit is completed through the actuating coil 33^f of the drum 1 to the negative conductor 48. The drum is thus actuated to its "forward" position, whereupon the circuit of the coil 33^f is interrupted.

- 30 35 The necessity for the two actuating coils 33^f and 33^r arises from the fact that otherwise reliable multiple-unit or train operation of a plurality of vehicles embodying my motor-reversing drums would not obtain. A single coil is satisfactory where no multiple-unit operation is intended, but when a train of vehicles is governed from a single master controller and a single master reverser, as is customary, a set of "back-40 stair circuits" or undesirable and unintentional connections are set up between the actuating-coil-governing contact members on different vehicles that are coupled together while their motor-reversing drums occupy 45 opposite or non-corresponding positions.

- 50 55 More specifically stated, the energization of one fluid-pressure-operated device 6, if a single actuating coil were used, would not be completed before an unintentional energization of the corresponding device on the other vehicle in question through the usual train-line conductors would cause the actuation of that device, and thus the motor-reversing drums could not be remotely controlled to cause them to assume like positions, but the train operator would be forced to manually throw the motor-reversing drum on one car.

60 However, by the use of two separate coils, 65 respectively corresponding to forward and

reverse operation of the motor, the above-mentioned difficulty is entirely obviated and reliable multiple-unit operation may be effected.

Without further description, it will be understood that suitable manipulation of the master reverser 39, when the motor-reversing drum 1 occupies a non-corresponding position, will cause the fluid-pressure-operated device 6 to be actuated to effect a successive advancing and retracting movement of the pawl 21, whereby the ratchet member 20 and the drum 1 are always moved in the same direction through a plurality of positions, each of which reverses the motor connections with respect to the next previous position.

I do not wish to be restricted to the specific structural details and arrangement of parts herein set forth, as various modifications thereof may be effected without departing from the spirit and scope of my invention. I desire, therefore, that only such limitations shall be imposed as are indicated in the appended claims.

I claim as my invention:

1. The combination with a rotatable motor-reversing drum, of a fluid-pressure-operated device for actuating said drum in a step-by-step manner in the same direction to reverse the motor connections with each step, controlling means for said device, and means dependent upon the position of said drum for governing said controlling means.

2. The combination with a rotatable motor-reversing drum, of a fluid-pressure-operated device for actuating said drum in a step-by-step manner in the same direction to reverse the motor connections with each step, and a controlling valve for said device dependent for actuation upon the position of said drum.

3. The combination with a rotatable motor-reversing drum, of a fluid-pressure-operated device for actuating said drum in a step-by-step manner in the same direction to reverse the motor connections with each step, and an electrically-governed controlling valve for said device, said valve being energized through contact members upon said drum.

4. The combination with a rotatable motor-reversing drum, of a fluid-pressure device embodying a piston member advanced by fluid pressure from a normal biased position to actuate said drum in the same direction through a plurality of operative positions to alternately effect "forward" and "reverse" connections of the governed motor, controlling means for said device, and means dependent upon the position of said drum for governing said controlling means.

5. The combination with a rotatable motor-reversing drum, of a fluid-pressure device embodying a piston member advanced

by fluid pressure from a normal biased position to actuate said drum in the same direction through a plurality of operative positions to alternately effect "forward" and 5 "reverse" connections of the governed motor, and a controlling valve for said device dependent for actuation upon the position of said drum.

6. The combination with a rotatable 10 motor-reversing drum, of a fluid-pressure device embodying a piston member advanced by fluid pressure from a normal biased position to actuate said drum in the same direction through a plurality of operative positions to alternately effect "forward" and 15 "reverse" connections of the governed motor, and an electrically-governed controlling valve for said device, said valve being energized through contact members upon said drum.

7. The combination with a rotatable 20 drum having a plurality of successively arranged sets of main contact members for motor-reversing purposes, of a ratchet member secured to said drum, a fluid-pressure device embodying a piston member advanced by fluid pressure from a normal biased position to engage said ratchet and actuate said 25 drum in the same direction through a plurality of positions corresponding to said sets of contact members, and a controlling valve for said device having an actuating coil, said drum being also provided with a 30 plurality of successively arranged sets of auxiliary contact members for completing the circuit of said coil under predetermined 35 conditions to effect movement of said drum.

8. The combination with a rotatable 40 motor-reversing drum, of single power means having a plurality of actuating coils for actuating said drum in the same direction through a plurality of positions to alter-

nately effect "forward" and "reverse" connections of the governed motor, said actuating coils being alternately connected in 45 operative relation to said power means.

9. The combination with a rotatable 50 motor-reversing drum, of a fluid-pressure-operated device having a plurality of alternately-employed coils for actuating said drum in a step-by-step manner in the same direction to reverse the motor connections with each step.

10. The combination with a rotatable 55 motor-reversing drum, of a fluid-pressure-operated device for actuating said drum in a step-by-step manner in the same direction to reverse the motor connections with each step, and a controlling valve for said device having a plurality of actuating coils, said 60 coils being alternately energized through contact members upon said drum.

11. The combination with a rotatable 65 drum having a plurality of successively arranged sets of main contact members for motor-reversing purposes, of a ratchet member secured to said drum, a fluid-pressure device embodying a piston member advanced by fluid pressure from a normal biased position to engage said ratchet and actuate said 70 drum in the same direction through a plurality of positions corresponding to said sets of contact members, and a controlling valve for said device having a plurality of actuating coils, said drum being also provided with a 75 plurality of successively arranged sets of auxiliary contact members for alternately completing the circuits of said coils to effect step-by-step movement of said drum.

In testimony whereof, I have hereunto 80 subscribed my name this 29th day of May, 1917.

LYNN G. RILEY.
